Patented Aug. 11, 1914.

UNITED STATES PATENT OFFICE.

GEORGE HILLARD BENJAMIN, OF NEW YORK, N. Y.

ELECTRIC FURNACE.

1,106,486.

Specification of Letters Patent. Patented Aug. 11, 1914.

Application filed December 19, 1913. Serial No. 807,684.

To all whom it may concern:

Be it known that I, GEORGE HILLARD BENJAMIN, a citizen of the United States, residing at New York city, in the county and State of New York, have invented certain new and useful Improvements in Electric Furnaces, of which the following is a specification.

My invention relates to an improvement 10 in electric furnaces, and consists in various details of construction, which will be fully set forth in the specification, and specifically pointed out in the claims.

The object of my invention is a construction 15 by reason of which the metallurgical operations taking place in the furnace are more readily and perfectly accomplished, than in prior constructions, and further, the effect of the evolved gases neutralized and 20 the action of free silica upon the furnace walls avoided.

The accompanying drawings, which are largely diagrammatic, will serve to illustrate the main features of the construction 25 of the furnace and also serve to aid in the description of the method employed in operating the furnace.

Referring to the drawings; Figure 1 is a vertical section of a furnace taken on the 30 line I—I of Fig. 2. Fig. 2 is a vertical section taken on the line II—II of Fig. 3. Fig. 3 is a top view, with a portion of the cover broken away to illustrate one form of construction for the bottom of the crucible. 35 Fig. 4 is a vertical section taken on the line IV—IV of Fig. 3, and Fig. 5 is a partial horizontal section illustrating a modified form for the bottom of the crucible.

In the drawings 10 indicates a closed 40 magnetic core, made of laminated plates and having the shape usual in transformer construction, that is, provided with a top portion, 11, a bottom portion 12, side portions 13 and a central portion 14. The core 45 10 is mounted on channel irons 15, secured to rockers 16, which rockers are mounted on roller bearings 17, located in the concave supports 18. Situated on top of the channel irons 15 and arranged transversely, are 50 channel irons 19, and mounted on the top of these channel irons is a ring 20, provided with an upwardly projecting portion 21, which serves as a guide for a series of channeled rollers 22. Mounted and supported 55 by the plate 20, is a disk shaped coil of wire 23, and supported on core 10 is a tubular

coil of wire 24. These two coils form the primary circuit and are connected in series to the terminals of a source of alternating current A. Situated over the coil 23 and surrounding coil 24, is an annular crucible 60 25. This crucible is mounted upon a ring 26, having a depending portion 27, which rests upon the channeled rollers 22. On the outside of the hearth is a metallic shell 28.

29 indicates a sectional cover for the top 65 of the crucible.

30 indicates a cavity in the crucible which acts as a hearth for the metal to be treated. Connected to the cavity 30 at its inner periphery, are ports 31 connected with an annular channel shaped member 32 which coacts with a channeled ring 33 supported above the coil 24, and which ring, through ports 34, communicates with a pipe 35 70 75 which may be connected with a pump or other similar apparatus (not shown) by reason of which the gases evolved by the metal under treatment may be exhausted, or conversely, gases or powdered bodies introduced over the metal on the hearth. The metal on the hearth is indicated by B.

Ring 26, which supports the crucible, is provided with gear teeth 36 on the lower side of its periphery, which coact with a gear 37 mounted on the left hand end of shaft 38. On the right hand end of shaft 38 is a gear 39, which coacts with a worm 40 on a shaft of motor 41. It will be understood that by reason of this last described 90 arrangement, circular motion may be imparted by the motor 41 to the crucible 25.

In Figs. 3 and 4 the bottom of the crucible or hearth 25 is provided with a series of curved upwardly projecting ribs 42, and in Fig. 5, with a series of straight radial ribs 43, the object of which ribs is to impart movement to the lower portion of the metal B in the crucible, when the crucible is rotated. In the construction shown in Figs. 100 3 and 4, the action of the ribs is to cause an inward movement of the body of metal, i. e., a movement toward the interior of the hearth, whereas in the arrangement shown in Fig. 5, it is to cause an outward movement toward the periphery of the crucible.

My improved furnace may be operated as follows: The metal B to be treated, together with such fluxes as are required, are charged into the cavity 30 of the crucible 25. As 110 such metal and the crucible form the secondary of the transformer, the metal will

be heated by induction to a high temperature. Further, the metal being fluid, will be subject to the repulsive action of the primary current, and its surface will take an angular inclination, as illustrated in Fig. 1. Such angular inclination is objectionable, as the amount of flux employed must be increased in accordance with the degree of inclination, *i. e.*, the greater the inclination the greater amount of flux. It is therefore desirable to decrease this inclination by mechanical means or otherwise. In practice I find the angular inclination may be decreased by rotating the crucible and subjecting the metal upon the hearth to the action of a mechanical force, *i. e.*, the force exerted by the ribs 42 and 43, which will move the bottom of the metal inward or outward, and thereby not only reduce the angular inclination but create a circulation of the metal across the hearth and circumferentially within the hearth.

In practice I prefer to rotate the crucible at a low speed, as for instance, ten revolutions a minute, for say five minutes, and then reverse the movement for a corresponding length of time. It is desirable to increase the speed as the fluidity of the material increases, and also effect reversals at shorter intervals.

I am aware that it has heretofore been suggested to rotate the whole furnace, including the electrodes in a circular direction and give it oscillatory movement, but such method I find to be open to many objections. My plan differs therefrom in that the major portion of the furnace is fixed and only the crucible is rotated, thus requiring very much less power and permitting greater facility of movement, and therefore a more perfect control of circulation of the material under treatment in the crucible.

After the material and fluxes introduced into the crucible are heated to the required temperature, I prefer to exhaust the evolved gases through the ports 31 and annular channel shaped member 32 and pipe 35. The object of doing this is two fold. First, to reduce the pressure of the evolved gases over the material under treatment and thereby remove any reactive force tending to prevent free evolution of gas, and second, to instantly remove the evolved gases as generated, thereby preventing their reabsorption. Very many gases evolved from the treatment of iron are liable to be split up into their elements when subjected to the very high temperature of an electric furnace, as for instance, sulfureted hydrogen, in which case there is liability of explosion of the hydrogen and the reincorporation of the sulfur with the iron, unless taken up by the slags. The gases evolved will depend not only upon the materials associated with the metals, but also upon the materials asso-

ciated in the fluxes or slags. These materials, owing to the high temperature and oxidizing action to which they are subjected, will be broken up or separated, some of them rising to the top of the slag level, as for instance, SiO_2 , which will attack the walls of the hearth, thereby requiring frequent renewals of the walls. To overcome this objection, I may introduce through the pipe 35, annular channel shaped member 32, and ports 31, magnesite (MgCO_3) which will combine with the silicon dioxide set free, and prevent its destructive action. Further, I may introduce through the pipe 35, annular channel shaped member 32, and ports 31, a neutral gas such as nitrogen under pressure, which will prevent the access of atmospheric air from the exterior of the furnace to the metal under treatment or to the fluxes, and thus prevent oxidation. Or I may introduce any gas, gaseous body or powdered body which will chemically combine with the fluxes, with the metal under treatment, or with any bodies carried by the metal, such for instance as the hydro-carbons, the ferro compounds, titanium, magnesium, manganese or other metals.

I wish it understood that it is within the contemplation of my invention to introduce any gas, liquid, powder, or combination of gases, liquids or powders, or all of them, which may be found useful or desirable.

The chemistry of the bodies, such as described, under the high temperatures of induction furnaces, is not now fully understood and I therefore am unable to make a more technical description of the actions and reactions which it is desirable shall take place in the treatment of metals of any character or of slags of any kind in an induction furnace.

What I wish to have understood is that I believe I am the first to suggest the introducing into the crucible and the metal or fluxes in the crucible, of a gas, gases, liquid or powdered bodies for the purpose of producing chemical reactions differing from such as are accomplished by the introduction of bodies in mass, as by shoveling in fluxes or combining bodies. I would further state that it is within the contemplation of my invention to not only introduce such bodies over the surface of the materials under treatment, but through the material under treatment, as for instance, from below, as in the manner in which air is introduced through the metal in a Bessemer converter. I have not, in this application, described any specific construction, leaving it to be made the subject of an application to be hereafter filed.

Having thus described my invention, I claim:

1. An induction furnace comprising a closed metallic core, a fixed primary, a mov-

- able secondary formed by an annular crucible and a body of metal therein, together with means for rotating the secondary relative to the core and primary.
5. An induction furnace comprising a closed metallic core, a fixed primary, a movable secondary formed by an annular crucible and a body of metal therein, means for rotating the secondary relative to the core and primary, and means communicating with the crucible for exhausting gases therefrom or introducing bodies thereto.
3. An induction furnace comprising a closed metallic core, a fixed primary, a movable secondary formed by an annular crucible and a body of metal therein, means communicating with the crucible for exhausting gases therefrom or introducing bodies thereto, and means for rotating the secondary relative to the core and primary.
4. An induction furnace comprising a closed metallic core, a fixed primary, a movable secondary formed by an annular crucible and a body of metal therein, said crucible having upwardly projecting ribs in the bottom thereof, together with means for rotating the secondary relative to the core and primary.
5. An induction furnace comprising a closed metallic core, a fixed primary, a mov-
- able secondary formed by an annular crucible and a body of metal therein, means for rotating the secondary relative to the core and primary, said crucible having a sectional detachable cover.
6. An induction furnace comprising a closed metallic core, a tilting, non-rotary primary, a rotary secondary formed by an annular crucible and a body of metal therein, together with means for rotating the secondary relative to the core and primary.
7. An induction furnace comprising a closed metallic core, a non-rotary primary, a rotary secondary formed by an annular crucible and a body of metal therein, ports and passages connected to said crucible and rotating therewith, a fixed pipe for the introduction of bodies into or the withdrawal of bodies from the crucible operatively connected with said passages and said crucible, together with means for rotating the crucible relative to the fixed portion of the furnace.

In testimony whereof, I affix my signature, in the presence of two witnesses.

GEORGE HILLARD BENJAMIN.

Witnesses:

HELEN E. KOELSCH,
C. A. HANSSON.
